(57) **CLAIM**

The ornamental design for a battery operated motor driven backpack sprayer, as shown and described.

DESCRIPTION

FIG. 1 is a perspective elevational view from the front of a battery operated motor driven backpack sprayer showing my design;

FIG. 2 is a perspective elevational view from the right side thereof;

FIG. 3 is a perspective elevational view from the left side thereof;

FIG. 4 is a top view thereof;

FIG. 5 is a bottom view thereof; and,

FIG. 6 is a perspective elevational view from the rear thereof.

1 Claim, 6 Drawing Sheets
